GAME APPARATUS

Eugene La Tocha, Cleveland, Ohio

Application June 3, 1949, Serial No. 3,036

Term of patent 7 years

(Cl. D34—5)

To all whom it may concern:

Be it known that I, Eugene La Tocha, a citizen of the United States, and a resident of the city of Cleveland, county of Cuyahoga, State of Ohio, have invented a new, original, and ornamental Design for a Game Apparatus, of which the following is a specification, reference being had to the accompanying drawings, forming part thereof.

Fig. 1 is a perspective view of the game apparatus, showing my new design;

Fig. 2 is a top plan view thereof;

Fig. 3 is a side elevational view thereof; and

Fig. 4 is an end elevational view thereof.

The drawing figures are lined to show color contrast.

I claim:

The ornamental design for a game apparatus, as shown and described.

EUGENE LA TOCHA.
